UNITED STATES PATENT OFFICE

159,459

TELEVISION RECEIVER CABINET

Samuel E. Adler, Chicago, Ill.

Application January 21, 1949, Serial No. 374

Term of patent 14 years

(Cl. D56—4)

To all whom it may concern:

Be it known that I, Samuel E. Adler, a citizen of the United States, and resident of Chicago, in the county of Cook, State of Illinois, have invented a new, original, and ornamental Design for a Television Receiver Cabinet, of which the following is a specification, reference being had to the accompanying drawings, forming a part thereof.

Fig. 1 is a front perspective view of a television receiver cabinet, showing my new design;

Fig. 2 is a horizontal fragmentary sectional view taken on line 2—2 of Fig. 1;

Fig. 3 is a vertical fragmentary sectional view taken on line 3—3 of Fig. 1;

Fig. 4 is a vertical fragmentary sectional view taken on line 4—4 of Fig. 1; and

Fig. 5 is a vertical fragmentary sectional view taken on line 5—5 of Fig. 1.

The dominant features of my design reside in that portion shown in full lines on the drawings.

I claim:

The ornamental design for a television receiver cabinet, as shown and described.

SAMUEL E. ADLER.
